UNITED STATES PATENT OFFICE.

EMORY STOCKWELL AND HERBERT C. STOCKWELL, OF STAMFORD, CONNECTICUT, ASSIGNORS TO THE YALE & TOWNE MANUFACTURING COMPANY, OF SAME PLACE.

TIME-LOCK.

SPECIFICATION forming part of Letters Patent No. 290,609, dated December 18, 1883.

Application filed September 11, 1883. (No model.)

To all whom it may concern:

Be it known that we, EMORY STOCKWELL and HERBERT C. STOCKWELL, both of Stamford, in the county of Fairfield and State of Connecticut, have invented certain new and useful Improvements in Time-Locks, of which the following is a specification, reference being had to the accompanying drawings.

Our present invention is an improvement upon the time-lock patented to Emory Stockwell, one of the parties hereto, in the United States, January 9, 1877, No. 186,177, in which is shown a supplementary unlocking device; and our purpose is to provide against any possible trouble from the operation of the supplementary-unlocking device at a time when it may be undesirable.

In a patent of said Emory Stockwell, No. 168,062, granted September 21, 1875, means are provided for protecting a time-lock from injury by concussion of any sort. These means are the use of springs in which the movement is cushioned. Experiments have proved that by a proper arrangement of springs the time-locks constructed in accordance with the patents of said Emory Stockwell will not be injured by concussion. In some situations, however, it may be desirable to guard against sudden springing of the supplemental unlocking device by very heavy concussions, which springing would cause the lock to unlock. To prevent any damage of this sort is the object of our invention, and we accomplish this object by means of a pin which passes through the back plate of the lock-case, and extends against or almost against the inner surface of the door of the safe or vault to which the lock is applied. Between the lock-case and the door are rubber washers around the bolts which hold the lock to the door. These rubber washers permit, under a heavy concussion, the door and lock to approach each other. The result of this approach will be to drive the pin into the path of the stud or

ledge of the supplemental unlocking device and lock it fast, so that it cannot operate.

In the accompanying drawings, Figure 1 is a front view, partly in section, of the said time-lock with our improvement applied; and Fig. 2 is a section of the same on the line 2 2 50 of Fig. 1.

In these drawings, A indicates the bolt or dog of the time-lock, pivoted at B, and provided with a supplemental unlocking device, C, having a stud or latch, D, which engages 55 with one of the triggers E F, all these parts being constructed, arranged, and operating as set forth in the said patent (No. 186,177) of Emory Stockwell.

G indicates a pin secured in any suitable 60 way in the time-lock case, and projecting back almost in contact with the inner plate of the door F at one end, and standing normally out of the path of the stud D at the other end, as clearly shown in Fig. 2. Whenever a con- 65 cussion takes place outside the door of sufficient force to endanger the engagement of the triggers of the supplemental unlocking device, this pin will be driven inward, as indicated in dotted lines in Fig. 2, so as to extend in the 70 path of the stud D and prevent the operation of the supplemental unlocking device.

We are aware that it is not new to provide a pin of this character adapted to be driven inward to serve a useful purpose in preventing the unlocking of a time-lock, such a device having been patented by said H. C. Stockwell, and we therefore do not claim such a device, broadly; but

What we do claim as new, and desire to secure by Letters Patent of the United States, is—

1. The combination, with a lock-case of a time-lock having a supplemental unlocking mechanism, and cushioned and secured a 85 slight distance from a door, of a pin, G, projecting from its support in the case toward the door on which the lock is applied, and

projecting within the case, so as to stand normally out of the way of the action of the supplemental unlocking mechanism, but adapted to prevent the unlocking action of said mechanism when driven inward by concussion on the outside of the door, substantially as set forth.

2. The combination, with the triggers E F, the dog A, the supplemental unlocking device C, and its stud D, of the pin G, substantially as set forth.

In testimony whereof we have hereunto subscribed our names this 25th day of July, A. D. 1883.

EMORY STOCKWELL.
HERBERT C. STOCKWELL.
